UNITED STATES PATENT OFFICE.

GEORGE HAUBNER, OF CLIFTON SPRINGS, NEW YORK.

GAME OR PUZZLE.

1,186,395.

Specification of Letters Patent.

Patented June 6, 1916.

Application filed April 12, 1915. Serial No. 20,805.

To all whom it may concern:

Be it known that I, GEORGE HAUBNER, a citizen of the United States, residing at Clifton Springs, in the county of Ontario 5 and State of New York, have invented certain new and useful Improvements in Games or Puzzles, of which the following is a specification.

My invention relates to an improvement 10 in games or puzzles, and it comprises a box having a false bottom with holes therein suitably spaced apart, and partitions having recesses therebetween, thus dividing the false bottom into compartments, and a 15 movable object, such for instance as a ball, which is intended to be moved or rolled from one compartment to another, the trick being to do this without permitting the movable object or ball to drop into any of 20 the holes.

In the accompanying drawings:—Figure 1 is a plan view; Fig. 2 shows the blank from which the bottom is made; Fig. 3 is a 25 cross section taken on the line 3—3 of Fig. 1; Fig. 4 is a detached view of one of the partitions.

A, represents the box, and 1 is the false bottom, preferably made of a blank as 30 shown in Fig. 2, with the four edges 3, 3, secured for the purpose of folding them at right-angles as a means of support for the false bottom at the edges, and for 35 gluing or otherwise securing the false bottom within the sides of the box, which the false bottom is made to fit. Slits 4, 4, are made in the bottom to receive the 40 partitions 5, 5, which preferably extend both above and below the false bottom to divide the surface of the false bottom into the three compartments 6, 7 and 8, and also to extend

to the bottom of the box to form support for the false bottom between its edges. These partitions come nearly together to allow sufficient openings 9 for the movable object or ball 10 to pass through. Holes 45 11, 11, are formed in the central compartment 7 in the direct path from the opening 9.

The game is played, or the puzzle is worked by holding it preferably in one hand, and so manipulating it as to cause 50 the movable object or ball 10 to move across from one compartment 6 to the other 8 without dropping into one of the holes 11, the space between the holes being sufficiently large to admit of this, if the hand of the 55 operator is sufficiently steady to guide the movable object or ball around the holes or pitfalls in its path.

This game or puzzle is not only entertaining and a test of skill, patience and steadiness of the nerves of the operator, but also 60 it is capable of being easily and inexpensively made and marketed.

I claim:

A game or puzzle comprising a box, a 65 false bottom, the edges of which are bent and secured to the box, said false bottom having slits therein, partitions in said slits where they are secured and extending both above and below the false bottom to divide 70 the latter into compartments and also support it between its edges, the central compartment having holes therein opposite the openings between the ends of the partitions.

In testimony whereof I affix my signature in the presence of two witnesses.

GEORGE HAUBNER.

Witnesses:

ELLIS MARTINWELD,
JOHN BURKE.
